METERED BOTTLE OPENER

Hubert James Walsh, 822 Arlington Road, Park Hills, Ky., assignor of one-half to Eugene H. Schaffner, Ludlow, Ky.

Filed June 8, 1959; Ser. No. 818,822.

8 Claims. (Cl. 81—3.1)

This invention relates to a bottle opener which automatically counts the number of bottles opened.

In these times of efficient selling where proprietors of restaurants and bars are required to carry large inventories in order to satisfy a public which demands quick service, it is important that devices be provided to maintain an accurate check on the inventories involved so as to guard against loss and pilfering. It will be appreciated that where a heavy business in bottled beverages exists, there will be the opportunity for both intended and unintended error by the counterman handling the goods. Normally, these errors are not discovered until a full inventory is taken and this is not regularly done by most concerns but a few times a year.

The instant invention provides an accurate means of maintaining a running account of the number of bottles opened by any particular opener. This invention allows a proprietor of an establishment dealing in bottled beverages to check his unit sales at any particular time so as to enable him to check out his cash receipts and provide him with information relating to the over-all status of his inventory.

It is another purpose of this invention to provide a mechanically metered opener which will not register unless a cap is actually removed from a bottle by the use of the opener.

A further purpose of the instant invention is to provide a bottle cap receptacle designed so that its contents are inaccessible, thereby affording a means of counting the number of caps, and thereby determining both the number, and different kinds of bottled beverages opened by the opener.

Another object of the invention is to provide a metered bottle opener inventory device which can be used in co-operation with other inventory devices to provide for an accurate means of establishing the running inventory of a restaurant, bar or other establishment dealing in bottled beverages.

For the attainment of these and such other objects as may appear or be pointed out, I have shown an embodiment of my invention in the accompanying drawing, wherein:

Figure 1 is a perspective view of the device having its cover and cap receptacle mounted thereon.

Figure 2 is a front elevational view of an opener device incorporating the principles of the invention.

Figure 3 is a side elevational view thereof.

Figure 4 is a cross sectional view taken along lines 4—4 of Figure 2 in which the device is shown in its non-actuated position.

Figure 5 is a cross sectional view similar to Figure 4 showing the device in its actuated position.

Metered bottle openers of the past have been designed so that the metering system would record faulty attempts at bottle opening as well as successful attempts, thereby causing the meter reading on the device to be actually in error. The instant device solves this problem by

2

presenting a metered bottle opener designed so as to register only when a bottle cap is actually removed.

With reference to Figure 2, it may be seen that the invention comprises an opener 1, mechanical linkage 9, mechanical counter 2, and mounting plate 11. With reference to Figure 2, it may be seen that opener portion 1, which is attached to mounting plate 11, is comprised of a conventional claw-type opener hook 3 and a vertically movable contact plate 4. Contact plate 4 is provided with a rolled contact edge 6. The cooperation of opener hook 3 and contact edge 6 in contacting and removing a bottle cap is illustrated in Figures 4 and 5.

As can be seen from Figure 2, contact plate 4 is integral with the lower portion of vertically movable slide, or piston 7, which is contained in guide, or guide sleeve 8. Guide sleeve 8 is attached to mounting plate 11 as is illustrated in Figures 4 and 5. The upper portion of slide 7 is provided with a slot 17 which receives an operating lever or arm 12. It may be seen from Figure 2 that slot 17 is provided with a hardened bearing pin 18 which contacts the lower edge 19 of operating lever 12 so that lower edge 19 does not contact the bottom 21 of slot 17. Due to this fact, it is not necessary to machine a bearing V or rolled edge in the bottom of the slot and consequently the slot may be formed by casting.

As may be seen in Figure 2, operating lever 12 is pivotally joined to mounting plate 11 by pivot pin 13 at one end, and connected to the upper portion of spring 14 by connecting pin 22 at the other. The lower portion of spring 14 is connected to mounting plate 11 by connecting pin 16.

In view of the connections just described, it will further be seen, with reference to Figure 2, that the tension of spring 14 tends to resist upward movement of slide 7 through operating lever 12 and normally urges slide 7 downwardly against stop plate 23. Stop plate 23 is attached to mounting plate 11 by means such as screws 24. It will be noted that if stop plate 23 is removed by unscrewing screws 24, slide 7 can also be removed for inspection or replacement and at the same time spring 14 will be relaxed so that it might be more easily inspected or replaced. The tension of spring 14 contributes to the accuracy obtained by the device and will be more fully described later.

With reference to Figure 3, it may be seen that mechanical counter 2 is provided with a counter arm 26 which operates the counter and a counting dial 5 which provides a reading of the number of times the counter has been actuated. Counter 2 is of the spring-loaded, "self-return" type so that counter arm 26, after being moved to the operating position so as to cause the counter to record, will automatically return to its inoperative position upon being released. It will be seen that one end of counter arm 26 is attached to the counter 2 and that the other end is linked to operating lever 12 by means of spring 27. Other types of linkage would be suitable to make this connection, but the spring means disclosed is preferred so that should the operating lever be over-extended for any reason, it could not bring damaging stress to bear on counter arm 26 as the spring connector 27 would absorb any force tending to damage the counter arm.

The operation of the device is best disclosed with reference to Figures 4 and 5. Figure 4 discloses the device freshly engaged with a bottle 28 which is covered by a conventional circular bottle cap 29 having a flat upper surface 31 and depending, fluted, circular gripping skirt 32. The bottle is inserted into the opener at such an angle as to cause the lower edge of the upper surface 31 of the cap to abut the under surface of rolled contact edge 6, and the upper edge of fluted skirt 32 to engage opener hook 3. As pressure is exerted downwardly on the lower

portion of the bottle, as is indicated by arrow 33, contact edge 6 tends to hold one edge of bottle cap 29 down firmly on the bottle while opener hook 3 engages the under portion of fluted gripping skirt 32. As the lower portion of the bottle is forced further downwardly, as is indicated by arrow 34, the upper portion of the bottle pivots on the contact made by the bite of opener hook 3 under the upper edge of skirt 32 causing slide 7 and contact plate 4 to be cammed upwardly by the contact of the upper surface 31 of the bottle cap with the under surface of rolled contact edge 6.

As slide 7 is cammed upwardly, the lower portion of operating lever 12, a portion of the lower edge of which resides within slide slot 17 (against bearing pin 18), is pivoted upwardly against the tension of spring 14. As the lower portion of the bottle is urged further downwardly, the tension of spring 14 becomes greater than the force tending to hold gripping skirt 32 on the bottle and at this moment opener hook 3 pries the edge of gripping skirt 32 away from the bottle, causing the cap to be removed. It will be appreciated that the connecting spring 27 drives counter arm 26 upwardly along with the upward movement of the lower portion of operating lever 12, actuating the counter mechanism and thereby recording the removal of the bottle cap 29. As soon as the cap is released, the bottle is removed from the opener and the tension of spring 14 pivots the lower portion of operating lever 12 back downwardly until slide 7 drives the lower edge of contact plate 4 against stop plate 23.

It is to be appreciated that quite often attempts to dislodge a bottle cap are frustrated by imperfect "bites" between the bottle cap and the bottle opener hook. Since many more initial contacts will be made than bottle caps removed, it is important that a device of the instant class be designed so as to provide a means of distinguishing between successful and unsuccessful attempts at bottle cap removal. This distinguishing factor is necessary to provide an accurate recordation of the number of caps actually removed as opposed to recording both successful and unsuccessful removal attempts. This distinguishing characteristic is provided in the instant invention.

It will be appreciated that slide 7 and the lower portion of operating lever 12 (to which the counter arm is connected) must move a certain predetermined distance upwardly before the counting mechanism is actuated. It will be further appreciated that the tension of spring 14 provides the opposing force to the upward movements of the operating lever and the slide. The instant device is designed so that the tension of spring 14, which opposes the upward movement of the operational elements (the slide and operating lever), consequently opposing activation of the counter, is great enough so that these operational elements will not be cammed upwardly sufficiently far enough to activate the counter unless the "bite" or engagement between opener hook 3 and gripping skirt 32 is severe enough to guarantee removal of the bottle cap. In other words, the upward movement of the elements activating the counter and the force opposing their movement is related to the pivotal engagement between the opener hook and the bottle cap skirt in such a manner that this pivotal engagement must be perfect enough to insure cap removal if the pivotal connection is to be maintained long enough to cam the operational elements for a sufficient distance to activate the counter. The force exerted against the operation of the counter (the tension of spring 14) is great enough so that should an improper "bite" or engagement be made between opener hook 3 and skirt 32 of the bottle cap, the engagement will be insufficient to overcome the force opposing counter activation, consequently, the imperfect engagement will be broken before the engagement has served as a pivot for a long enough time to cam the operational elements into counter operating position. In this way, faulty contacts between the bottle and bottle opener will

not cause the counter to operate and only those contacts perfect enough to insure cap removal will actually activate the counter.

Cover 36 for the device is shown in Figure 1. It may be seen that the cover is in the form of the conventional rectangular combination bottle opener cover and cap reservoir. The upper portion of the front face 37 of cover 36 is provided with a bottle opening aperture 38 and a counter dial window 39. The cover is a removable one, and is designed so that when it is affixed to mounting plate 11 the frame of counter dial window 39 is coincident with counting dial 5 of counter 2, thereby making it possible to read the dial through window 39 when the cover is in place. The cover may be locked to mounting plate 11 and mounting plate 11 may in turn be secured to a wall (not shown) in some convenient location.

As may be seen with further reference to Figure 1, the lower portion of cover 36 comprises a cap reservoir 41. The back wall 42 of the cap reservoir does not extend all the way to the top 43 of the cover, but instead ends at 44 so as to provide an area for the opening device to protrude into the upper portion of the cover. Bottle opening aperture 38 is designed to allow proper space for the insertion of a bottle so as to provide for optimum bottle opening action. It will be noted that the lower portion 46 is U shaped so as to fit the curved neck of a bottle being urged downwardly to pry the cap off. If desired, the back wall 42 of the cap reservoir may be integral with mounting plate 11 so that the opener is really mounted within the cover.

Although the size of bottle opening aperture 38 is not larger than that which is necessary to allow comfortable bottle opening action and consequently restricts the insertion of the hand or fingers to a great degree, flange 47 may also be provided to extend across a portion of the width and the entire cross section of the reservoir portion at a point immediately below the bottle opening aperture to further restrict any attempt to remove bottle caps through the bottle opening aperture. It may be seen that flange 47 is installed at an angle to the horizontal so that when a bottle cap removed by opener hook 3 falls downwardly, it strikes the flange and is deflected to one side and to the bottom of the reservoir 41.

With further reference to Figure 1, it may be seen that the lower portion of the reservoir is provided with hinged bottom plate 48. One end of bottom plate 48 is supplied with an apertured fastener portion 51, the aperture 52 of which cooperates with a locking eye 53 which extends from the side of the lower portion of the cap reservoir. It can be appreciated that when the bottom plate is swung upwardly so as to snugly engage the bottom cross section of the cap reservoir, locking eye 53 protrudes through fastener aperture 52 so as to enable the reservoir to be locked by such means as a padlock. The upper lip 54 of fastener portion 52 is bent outwardly at a slight angle to facilitate gripping in disengaging the bottom portion 38 so as to open the cap reservoir.

It will be appreciated that the locked bottle cap reservoir provides a means of double checking not only the number of caps opened by the bottle opener, but also the different kinds of bottles opened. This feature is important because an operator faced with a total appearing on the counter dial 5 might argue that the device was not functioning properly or that most of the bottles opened were soft drinks instead of premium beer.

The instant device may be utilized by itself or in combination with other similar devices. For instance, a proprietor serving both local and premium beers and soft drinks might arrange these three classes of beverages into single bins, placing one of the instant devices on

the side of each bin so that the number of bottle openings recorded by each device would signify the total number of opened bottles in each of the three categories; namely, premium or local beer and soft drinks.

In most instances, the instant device will operate in combination with other inventory control devices such as cash registers and physical inventory checks, however, it can be appreciated that it may be used as an inventory control device all by itself.

The device may be installed to a wall surface merely by attaching mounting plate 11 to a wall in some conventional manner (not shown) and the cap reservoir 41 may be locked to the mounting plate again in some conventional manner (not shown) so that it cannot be removed and its contents tampered with. In the event mounting plate 11 is integral with the back wall 42 of the reservoir, the entire unit may be installed on a convenient wall surface in like manner. In this instance, the opener portion is mounted on the back wall of the container, inside the container, so that the entire device is a single unit.

Having described my invention, I claim:

1. A bottle opener and counter for a metered bottle opening device having a mounting plate and a counting mechanism mounted thereon, means connecting said bottle opener to said counting mechanism, said bottle opener comprising a fixed element and a vertically slidably mounted element, both of said elements being mounted upon said mounting plate, said elements being positioned to receive the head of a capped bottle between them, resilient means resisting the movement of said slidably mounted element being mounted on said mounting plate adjacent said element, whereby the application of opening leverage being exerted upon said bottle causes the slidably mounted element to move vertically against said resilient means to actuate said counting mechanism through said connecting means.

2. A bottle opener and counter for a metered bottle opening device having a mounting plate and a counting mechanism mounted thereon, means connecting said bottle opener to said counting mechanism, said bottle opener comprising a fixed element and an element vertically slidable between two predetermined limits, resilient means urging said vertically slidable element to maintain a position adjacent one limit of its movement, both of said elements being mounted upon said mounting plate, said elements being positioned to receive the head of a capped bottle between them, whereby the application of opening leverage being exerted upon said bottle causes the slidably mounted element to move in opposition to said resilient means to actuate said counting mechanism through said connecting means.

3. A metered bottle opening device comprising a mounting plate, a counter mechanism, a bottle opener having a hook portion and a linearly movable contact portion, resilient means resisting the movement of said linearly movable contact portion being mounted on said mounting plate, means securing said counter mechanism, bottle opener and mounting plate together, means transferring movement of said movable contact portion to said counter mechanism in opposition to said resilient means to actuate said counter, an apertured cover for said metered bottle opening device, said cover having a locked bottle cap reservoir and being integral with said mounting plate.

4. A metered bottle opening device comprising a mounting plate, a self-return, spring-loaded counter mechanism having an actuating arm and a viewable dial, a bottle opener mechanism having a hook portion and a substantially vertically movable slide portion, resilient means resisting the movement of said movable slide portion being mounted on said mounting plate, a guide portion and a stop plate portion, means mounting said

hook, stop plate, and guide portions and said counter mechanism upon said mounting plate, a part of said slide portion being slidably mounted within said guide portion, the lower end of said vertically movable slide portion abutting said stop plate, means connecting the upper end of said slide portion to the actuating arm of said counter mechanism, said means transferring vertical movement of said slide portion to said counter actuating arm to actuate said counter.

10 5. A metered bottle opening device comprising a mounting plate, a self-return, spring-loaded counter mechanism having an actuating arm and a viewable dial, a bottle opener mechanism having a hook portion, a vertically movable contact portion, a guide portion, a stop plate portion and an apertured cover portion, spring tension means mounting said hook, stop plate, cover and guide portions and said counter mechanism upon said mounting plate, a part of said contact portion being slidably mounted within said guide portion, the lower end of said vertically movable contact portion being urged to abut said stop plate by said spring tension means, means connecting the upper end of said contact portion to the actuating arm of said counter mechanism, said means transferring vertical movement of said contact portion to said counter actuating arm overcoming said spring tension means to actuate said counter.

6. A metered bottle opening device comprising a mounting plate, a self-return, spring-loaded counter mechanism having an actuating arm and a viewable dial, a bottle opener having a hook portion and a vertically movable slide portion, adopted to receive the head of a bottle, a guide portion, a stop plate portion and an apertured cover portion, means mounting said hook, stop plate, cover and guide portions and said counter mechanism upon said mounting plate, a part of said slide portion being slidably mounted within said guide portion, the lower end of said vertically movable slide portion abutting said stop plate, resilient means resisting the movement of said movable slide portion, said means being fixed to said mounting plate, means connecting the upper end of said slide portion to the actuating arm of said counter mechanism, said means transferring vertical movement of said slide from the force of a bottle inserted in said opener in opposition to said resilient means to said counter actuating arm to actuate said counter, said cover portion enclosing said metered bottle opening device, one of said apertures in said cover framing the viewable dial of said counting mechanism, another aperture in said cover framing said bottle opener, the lower portion of said cover being provided with a bottle cap reservoir and means to lock said reservoir.

7. In a bottle opening device for use with a counter mechanism the improvement comprising a bottle opener and a mounting plate, said bottle opener having a bottle cap gripping portion and a bottle cap contact portion, said gripping portion being fixedly mounted upon said mounting plate and said contact portion being vertically slidably mounted upon said mounting plate, spring means urging said contact portion downwardly with sufficient force to require firm operable engagement of a bottle cap with both portions of said opener to raise said contact portion through the force applied to a bottle during removal of its cap.

8. In a bottle opening device including a counting mechanism, the improvement comprising a bottle opener and a mounting plate, said bottle opener having a bottle cap gripping portion and a bottle cap contact, said gripping portion being firmly mounted upon said mounting plate and said contact being vertically slidably mounted opposite to said gripping portion upon said mounting plate, yieldable means urging said vertically slidable contact toward its lowermost position on said

mounting plate, said contact and gripping portion positioned to relatively engage the underskirt and upper face of the cap of a bottle inserted therebetween, whereby upon application of leverage to the bottle to remove the cap, the cap first forces the contact upwardly a predetermined distance counter to said yieldable means, said yieldable means providing sufficient resistance to cause removal of the cap, said contact being connected

to the counting mechanism to actuate the same when the cap is removed.
